(57) **CLAIM**

The ornamental design for a combined desk with adjustable notebook support, as shown and described.

DESCRIPTION

FIG. 1 is a perspective view of a combined desk with adjustable notebook support, showing my new design; FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged detailed view of encircled area 9 in FIG. 1.

The broken lines show portions of the article that form no part of the claimed design.

1 Claim, 9 Drawing Sheets
